UNITED STATES PATENT OFFICE.

ALONZO A. WARNER, OF NEW BRITAIN, CONNECTICUT, ASSIGNOR TO LANDERS, FRARY & CLARK, OF NEW BRITAIN, CONNECTICUT, A CORPORATION OF CONNECTICUT.

ELECTRICAL CONNECTION.

Application filed February 1, 1923. Serial No. 816,261.

My invention relates to electrical connections, and has special reference to hinged connections for electrically connecting conductors carried by an operating handle with 5 conductors carried by the member to which said handle is hinged, without requiring the use of flexible conductors.

The principal object of the invention is to provide an electrical connection of this character which is so constructed that any normal wearing of the parts of the handle hinge will not in any way impair the efficiency of the connection.

Another object of the invention is to provide an electrical connection of this character which is of simple, strong and durable construction.

The following is a description of my invention, reference being had to the accompanying drawings, in which,

Figure 1 is a plan view, partly in section, of a portion of a vacuum cleaner to which an electrical connection is applied embodying the features of the invention in their preferred form; and

Figs. 2 and 3 are sectional views, partly in side elevation, taken on the lines 2—2 and 3—3, respectively, of Fig. 1.

In the drawings my invention is shown embodied in a vacuum cleaner having a body or casing 2, and a hinged operating handle or rod 4 having a cast socket 6 at its lower end. As shown, the handle hinge comprises spaced lugs 8 on the body or casing 2, lugs 10 formed on the handle socket and arranged adjacent the outer sides of the lugs 8, respectively, and a pivot pin or bolt 12 extending through apertures in the lugs 8 and 10, the bolt being fixed to the lugs 10 by means of a nut 14 which cooperates with the head of the bolt to clamp the lugs. The lugs 8 are provided with brass bushings 16 to provide bearings for the bolt or pivot pin. The handle is provided with a central bore 45 through which pass two electrical conductors 18, and the body or casing 2 carries two electrical conductors 20 having their inner ends connected with the terminals of the motor of the machine. The lower end of 50 each of the electrical conductors 18 is secured to the shank 22 of a terminal contact eyelet 24, and the outer end of each of the

electrical conductors 20 is secured to the shank 26 of a terminal contact eyelet 28. The contact eyelets 24 and 28 are of the usual construction, they being made of sheet metal with lips formed on their shank which are tightly bent around the end of the conductor. The eyelets 24 are pivotally mounted on sleeves 30 of insulating material that are mounted on the pivot pin 12 adjacent the inner sides of the hinge lugs 8, respectively. The eyelets 28 are also pivotally mounted on the sleeves 30 and arranged adjacent to and in contact with the outer faces of the eyelets 24, respectively. A collar or washer 32 of insulating material surrounds each sleeve 30 and is interposed between the eyelets 28 on the sleeves and the adjacent hinge lug 8. Two collars or blocks 34 of insulating material are loosely mounted on the pivot pin 12 between the two sets of contact eyelets and in contact with the eyelets 24, and each is countersunk on its inner face to provide seats for the ends of a spring 36 coiled about the pivot pin 12. The spring 36 yieldingly presses the blocks outwardly so as to cooperate with the abutment washers 32 to yieldingly, but firmly, press the eyelets together between them so as to maintain the eyelets in proper electrical contact. Each of the blocks is provided with a countersunk recess 38 in its outer face to enable the block to ride over the inner end of the adjacent sleeve 30 so as to engage the eyelets and maintain them in close contact in spite of any normal wear.

The eyelets 24 and 28 are connected with the operating handle 4 and the casing 2 so as to cause them to turn with these parts, respectively, and thus maintain proper electrical connection between the conductors 18 and 20 without bending the conductors when the operating handle of the cleaner is swung on its hinge. To provide for this each of the blocks 34 is provided with a longitudinally extending slot 40, and the handle socket 6 is provided with a projecting tongue 42 that enters the slots 40 and thus hold the blocks from turning movement with relation to the handle but permitting longitudinal movement of the blocks. The slots 40 also receive inwardly projecting portions of the shanks 22 of the contact eyelets 24 so that

these eyelets are also held from turning movement with relation to the handle and hence turn with the handle when the handle is swung on its hinge. The contact eyelets 5 28 are held in fixed position with relation to the casing 2 by means of bushings 44 of insulating material secured in apertures in the casing, and through which the shanks of the eyelets 28 extend, the shanks closely 10 fitting in the inner wall of the bushings.

From the foregoing it will be apparent that a simple, strong and durable electrical connection is provided which is particularly adapted for use on vacuum cleaners and 15 other electrically operated machines having a hinged operating handle that carries electrical conductors connected with the machine motor. It will also be apparent that the coiled spring 36 will maintain the contacts 20 24 and 28 in rubbing contact and hence in proper electrical engagement irrespective of any wearing of the parts of the handle hinge or any wearing of the contacts themselves, and that the contacts are well insulated 25 from the metallic parts of the machine handle and casing. The parts of the connection may be easily assembled and taken apart upon removing the pivot bolt 12.

As will be evident to those skilled in the 30 art, my invention permits of various modifications without departing from the spirit thereof or the scope of the appended claims.

What I claim is:—

1. The combination of two members having 35 a hinged connection between them comprising two adjacent perforated lugs located on said members, respectively, and a pivot pin extending through an aperture in each lug, terminal contacts arranged side by side and located on the same side of both of said lugs and surrounding said pivot pin, connections between said terminal contacts and said members to cause them to turn with said members, respectively, about the axis of said 40 pivot pin, one of said connections comprising a block of insulating material arranged at the opposite side of said contacts from both of said lugs and mounted to slide axially on said pivot pin and revolve with the far lug, a 45 spring acting on the block to cause it to co-operate with the nearest lug to yieldingly press said contacts toward each other, said block being located between said spring and the nearest of said terminal contacts and insulating said spring from said terminal contacts, and electrical conductors secured to 50 said contacts and carried by their associated members, respectively.

2. The combination of two members having 55 a hinged connection between them comprising two lugs mounted upon said members, respectively, a pivot pin, terminal contacts arranged side by side on the same side of both of said lugs and surrounding said pivot 60 pin, means for causing said contacts to turn

with said members, respectively, about the axis of said pivot pin, comprising a block of insulating material loosely mounted on the pivot pin having a longitudinally extending slot for receiving a tongue on one of said members and a projection on one of said contacts to hold said block and contact from turning movement with relation to said member but permitting axial movement of the block, a spring for axially pressing the block 75 in one direction toward both of said lugs, an abutment arranged to cooperate with said spring-pressed block and cause said block to press said contacts toward each other, and electrical conductors secured to said contacts 80 and carried by their associated members, respectively.

3. The combination of two members having 85 a hinged connection between them comprising two pairs of lugs having their corresponding elements mounted on said members, respectively, a pivot pin, two pairs of terminal contacts spaced apart and mounted on said pivot pin between said pairs of lugs with the contacts of each pair arranged side 90 by side in electrical contact, and adapted to be relatively turned about the axis of the pivot pin, connections between one of the contacts of each pair and one of said members comprising two blocks loosely mounted 95 on said pivot pin having connections with said member for holding the blocks from turning movement with relation to said one member and having connections with said contact of each pair to hold said contacts 100 from turning movement with relation to said blocks and said one member, connections between the other terminal contact of each pair and the other hinged member, a spring coiled about the pivot pin and arranged between 105 the blocks for pressing the blocks outwardly in opposite directions, abutments surrounding the pivot pin and cooperating with the blocks to hold the contacts of each pair in electrical engagement, and electrical conductors secured to said contacts and carried by their associated members, respectively.

4. The combination of two members having 115 a hinged connection between them comprising two pairs of lugs having their corresponding elements mounted on said members, respectively, a pivot pin, two pairs of terminal contacts spaced apart and mounted on said pivot pin between said pairs of lugs 120 with the contacts of each pair arranged side by side in electrical contact and adapted to be relatively turned about the axis of the pivot pin, connections between one of the contacts of each pair and one of said members comprising two blocks movable in a direction parallel to the axis of said pivot pin and having suitable connections with said last mentioned member for holding them 125 from turning movement with relation to said 130

member, and having connections with said contact of each pair to hold said contacts from turning movement with relation to said blocks and said member, connections between 5 the other terminal contact of each pair and the other hinged member, means for yielding- ly pressing the blocks outwardly in opposite

directions, abutments cooperating with the blocks to hold the contacts of each pair in electrical engagement, and electrical conductors secured to said contacts and carried by their associated hinged members, respectively. ¹⁰
